UNITED STATES PATENT OFFICE.

SPENCER OTIS, OF CHICAGO, ILLINOIS, ASSIGNOR TO NATIONAL DUMP CAR COMPANY, A CORPORATION OF MAINE.

DUMPING-DOOR-OPERATING MECHANISM.

No. 887,837.

Specification of Letters Patent. Patented May 19, 1908.

Application filed April 24, 1906. Serial No. 313,464.

To all whom it may concern:

Be it known that I, SPENCER OTIS, a citizen of the United States, residing at Chicago, in the county of Cook and State of Illinois, have invented certain new and useful Improvements in Dumping-Door-Operating Mechanism, of which the following is a specification.

My invention relates to dumping door operating mechanism; and has for its object to provide an improved push-arm for use in mechanisms of this type.

My invention consists in the details hereinafter described and claimed.

In the accompanying drawing—Figure 1 is a transverse sectional elevation of part of a dump car, showing my invention applied thereto. Fig. 2 is a longitudinal elevation of my improved push-arm. Fig. 3 is a bottom plan view thereof.

In the drawing, I have shown in Fig. 1 a part of a dump car having a bottom comprising dumping doors e . e' is an operating shaft suitably connected by a crank arm e^2 25 and the push-arm—hereinafter described—to a reciprocating bar e^3 traveling on a track e^4 , which track is connected to the under side of the door. These parts are common and well-known in the art and need no further description.

My invention relates specifically to the construction of the push-arm connecting the crank e^2 with the reciprocating bar. This

push-arm comprises a channeled bar having an upper web or plate a with side flanges b 35 integral therewith. At its inner end, this push-arm is of sufficient width to receive, between the side flanges, the end of the crank e^2 , and at this end it is provided with suitable perforations c in its side flanges for 40 receiving a transverse hinge or pin c' for the crank arm. Toward its forward end the web of the channeled bar is narrowed, as at a' , forming a narrow forward extension a^2 —45 the side flanges being widened at these points, as at b' , b^2 . The widening of the side flanges is for the purpose of providing a sufficient space for the perforations d which receive the reciprocating bar e^3 —this bar being of greater diameter than the hinge of the crank arm. 50

My improved push-arm may be conveniently formed of pressed metal, as will be readily understood.

It will be seen that I have provided a push-arm which is exceedingly strong and well 55 adapted for the purpose for which it is used.

I claim:

A push arm for dumping door operating mechanism, consisting of a channeled bar having perforations in its flanges, the flanges 60 being widened and the web narrowed at one end of the door.

SPENCER OTIS.
